SLIDEWAY GRINDING MACHINE

Otto Bretscher, Gerlaingen, Switzerland, assignor to
Gesellschaft der Ludw. von Roll'schen Eisenwerke
A. G., Gerlaingen, Switzerland, a Swiss company

Application March 17, 1955, Serial No. 494,835.

Claims priority, application Switzerland March 20, 1954

4 Claims. (Cl. 51—3)

The present invention relates to a slideway grinding machine, particularly for grinding the slideways of the beds of lathes, planing machines, millers and grinders.

To render work of this nature less expensive, grinding machines have already been designed in which two grinding attachments are provided which are displaceable along the cross ways of the grinding machine so that at least two slideways can be machined simultaneously, irrespective of whether the sliding surfaces are flat or profiled. The beds of the abovementioned machine tools are as a rule provided with undergrip guides to secure the carriage moved along the slideways, which guides must be ground from underneath by means of dish grinding wheels.

It is therefore an important object of the invention to provide means contributing to a very compact and highly efficacious grinding machine of the aforesaid type which permits carrying out of a wide variety of grinding operations at utmost precision.

It is another object of the invention to provide means affording a highly economical performance of grinding operations simultaneously on upper and lower surfaces of a workpiece, whereby the superpositioned planes in which grinding is carried out, may overlap or stagger with respect to each other.

The purpose of the present invention is further to enable undergrinding to be carried out on a workpiece at the same time as the grinding of the top surface thereof is performed.

The invention more precisely contemplates the provision of cross rails or cross ways in grinding machines not only with guideways for the grinding wheel slide but also additional guideways in which at least one supporting slide with a vertically adjustable undergrinding attachment is mounted so that it can be displaced horizontally.

A typical embodiment of the invention is illustrated in the attached drawings in which:

Fig. 1 is a fragmentary front view of a slideway grinding machine with a workpiece chucked in position and two undergrinding attachments arranged on the cross ways of the machine;

Fig. 2 is a similar view on an enlarged scale of an undergrinding attachment seen in conjunction with the cross ways of the machine;

Fig. 3 is a cross-section taken along the line III—III in Fig. 2;

Fig. 4 is a top plan view of the attachment according to Fig. 2; and

Fig. 5 is a cross-section taken along line V—V in Fig. 2, the grinding spindle being axially adjustable in the vertical slide.

As will be seen from Fig. 1 of the drawing, the slideway grinding machine incorporating the present invention comprises a workpiece table generally indicated at 41 and having a table base 42 and a slidable top 43, the latter carrying a workpiece 44.

Above the workpiece table 41 and the workpiece 44 a crossways or supporting member 1 is disposed to ex-

2

tend horizontally and transversely with respect to said table, said crossways being mounted at one or both of its ends in vertical columns (not shown in the drawing), said crossways carrying two grinding wheels 45 by means of a slide 46 each.

On the lower surface of the cross ways or support 1, at the front of which guideways 2 are arranged for the grinding wheel slides 46, there is provided a recess or groove 3 with guideways 4 and 5 (Fig. 3). The supporting slide 6 is mounted in these guideways so that it can be displaced horizontally, and it is provided with a screwed-on threaded nut 7 through which the threaded guide spindle 8 passes. This supporting slide is provided with clamping bolts 12 and 13 which are hydraulically controlled by means of the handwheel 10. As is conventionally known, the spindle 8 is supported for rotation and against axial displacement in suitable bearings (not shown) located, for example, adjacent the opposite ends of the spindle. Either a handwheel or a constant-speed, generally reversible motor (not shown) may be drivingly connected to the spindle by any suitable means for the purpose of rotating said spindle. The slide 6 can thus be displaced horizontally by rotating the threaded spindle 8 mounted in the cross ways, independently of the grinding wheel slides 46 mounted in the aforesaid guideways 2. In the supporting slide 6 there is arranged, by way of example, a vertical dovetail guide 6a on which a vertical slide 14 is mounted.

Bolted to the slide 6 by means of bolts 15a is a flange 15 (Figs. 2 and 3) to which an internally threaded tube 16 is rigidly welded at right angles. The threaded spindle 17, which is mounted on ball bearings 18 and 19 in the housing 14a, engages in this internally threaded tube. On its lower end the spindle 17 has a handwheel 20, by means of which the spindle 17 can be rotated and the slide 14 roughly adjusted. Between the two ball bearings 18 and 19 a worm gear 21 is keyed on to the spindle 17. This gear is engaged by the fine adjusting worm 22 which is mounted on the shaft 22a and on which is arranged the handwheel 23, by means of which the slide 14 can be vertically adjusted during the fine infeed. The shaft 22a, on which the fine adjusting worm 22 is arranged, is eccentrically mounted in a rotatable bushing 22b and can be turned by means of the lever 22c so that the worm 22 can be disengaged from the worm gear 21 if a coarse feed has to be set. For the fine adjustment of the grinding wheel 29, the latter can also be mounted in a threaded bushing so that, by turning said threaded bushing or a threaded nut associated therewith, the said wheel can be finely adjusted without displacing the slide 14. Fig. 5 shows this adjusting device. The grinding spindle 27 can, as shown in Fig. 5, be mounted in an axially shiftable bushing 35 in the vertical slide. The said bushing 35 is provided with a thread 36 and held in a threaded nut 37 so that it is axially displaceable. The bushing 35 also has a toothed rim 38 which is engaged by the worm 39 mounted on the shaft 40. Coarse adjustment of the grinding wheel can be effected by turning the shaft 40 with the nut 37 locked, and fine adjustment by turning the nut 37. The vertical slide 14 has an arm-supported bearing 25 in which is mounted the bearing bushing 26 of the grinding spindle 27. Arranged on the grinding spindle 27 is the belt pulley 28 which engages in the groove 3 of the crossways 1, which groove opens in downward direction. Also mounted on the said spindle is a grinding wheel 29, of the dish type for instance. Secured to the grinding head 25—26—27—14—6 via arms 30 on the other side of the vertical slide 14 is a power driven means in the form of a motor 31, the belt pulley 32 of which also engages in the groove 3 of the cross-rail or support 1 and drives the belt pulley 28 of the grinding spindle 27 via the belt 33. The grinding wheel 29 can

therefore be adjusted both horizontally and vertically by means of the threaded spindle 8 of the cross ways 1 and the threaded spindle 17 in the vertical slide rest 14, respectively.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

1. In a slideway grinding machine having first and second grinding means for simultaneously grinding both upper and lower surfaces of a workpiece and equipped with a workpiece table movable relative to said grinding means; a horizontal support means extending above and across said workpiece table, first and second guideways provided on said support means and arranged in planes forming an angle to each other, means for slidably supporting said first grinding means along said first guideways, power driven means in driving connection with said second grinding means, said second guideways being located on the underface of said support means, horizontally movable slide means extending into said second guideways and supporting said power driven means, vertical slide means displaceably arranged on said horizontally movable slide means, said power driven means and said second grinding means being operatively connected with and displaceable by said vertical slide means relative to said horizontally movable slide means, means for actuating said vertical slide means, and means for operating said horizontally movable slide means independently of said vertical slide means, whereby said second grinding means may be moved along said second guideways via said horizontal slide means and may be vertically adjusted in position to said workpiece and said first grinding means by said vertical slide means.

2. In a slideway grinding machine according to claim

1, including bearing means, spindle means for said second grinding means and supported in said bearing means, said power driven means, said second grinding means and said horizontally movable slide means together with said vertical slide means being arranged as a unit for displacement relative to said first grinding means, said means for operating said vertical slide means being disposed intermediate said power driven means and said second grinding means.

3. In a slideway grinding machine according to claim 2, said bearing means of said second grinding means including externally threaded bushing means mounted for rotation on said vertical slide means, and internally threaded nut means in operative engagement with said externally threaded bushing means, whereby said second grinding means may be finely displaced in vertical direction upon rotational movement of said bushing means relative to said nut means and independently of the vertical adjustment of said second grinding means by said vertical slide means.

4. In a slideway grinding machine according to claim 1, said power driven means including motor means, and belt and pulley means drivingly connecting said motor means with said second grinding means, said horizontal support means being provided with a groove accommodating said belt and pulley means.
